No. 12,411

Aug. 16, 1881

UNITED STATES PATENT OFFICE.

GEORGE S. BARKENTIN, OF OCEANUS, NEW YORK, ASSIGNOR TO P. & F. CORBIN, OF NEW BRITAIN, CONNECTICUT.

DESIGN FOR A BRACKET.

SPECIFICATION forming part of Design No. 12,411, dated August 16, 1881.

Application filed July 1, 1881. Term of patent 14 years.

To all whom it may concern:

Be it known that I, GEORGE S. BARKENTIN, a citizen of the United States, residing at Oceanus, in the county of Queens and State of New York, have invented and produced a new and original Design for Brackets, of which the following is a specification, reference being had to the accompanying drawing, forming part thereof, which represents said bracket in perspective.

A designates the back, and B the arm, extending therefrom in the ordinary manner. Near the lower end of the back A there is a scroll-bar, a, from the outer end of which a vertical bar, b, extends upward to the transverse bar c. The space or panel inclosed by said bars and the back contains a conventional plant on a sunken and roughened ground. The bar c extends to the right of bar b, and in the corner 15 there is a quadrant-shaped brace, d. From the outer end of bar c a bar, C, extends upward parallel to the back until it begins to approach the arm B, when it curves to one side and extends parallel to said arm to the vertical bar e. Another horizontal bar, f, extends from the bar e toward the outer end of the arm B, and parallel thereto, and is connected to said arm by the scroll-bar g. The space inclosed by the bars e f g and the arm B is ornamented 20 by a row of triangular figures in relief, with a circular depression in the middle of each figure. The surface of the triangular spaces between said figures is fluted. A second vertical bar, h, extends from the arm B to the

curved portion of the bar C, and the space 35 inclosed by the bars h C e and arm B is ornamented in open-work by a branch and leaves. The space inclosed by the bars c C h, back A, and arm B is also ornamented in open-work, the principal figure in which represents a 40 crested stork. At the inside corner of the back and arm there is a fan or quadrant shaped figure, and upon the side of the bar h is the representation of a butterfly.

I claim—

1. The design for a bracket herein shown and described, the same consisting of the back A, scroll-bar a, vertical bar b, transverse bar c, the combined straight and curved bar C, bars e f, formed respectively transversely and 50 parallel to the arm B, and the scroll-bar g.

2. The design for a bracket herein shown and described, the same consisting of the bar C, the ends of which are parallel to the back and arm, respectively, and the middle portion 55 of which is curved, and open ornamental work connecting said bar to the back and arm.

3. The design for a bracket herein shown and described, the same consisting of the bars a b c C e f g, with ornamental open-work in the 60 space inclosed by bars c C e, arm B, and back A, the principal feature of which open-work is the representation of a stork standing on the bar c.

GEORGE S. BARKENTIN.
